UNITED STATES PATENT OFFICE

EMIL B. MEYROWITZ, OF NEW YORK, N. Y., ASSIGNOR TO E. B. MEYROWITZ, INC., A CORPORATION OF NEW YORK

GOGGLES

Application filed March 10, 1927. Serial No. 174,133.

My invention relates to goggles and particularly to the cushions which are a necessary part thereof, and means for attaching the cushions to the goggle frame.

5 Goggles are an essential part of the equipment of many workers in fields where conditions require eye protection. The operators of high speed transportation means, particularly the pilots of high speed aeroplanes, require goggles for the protection of their eyes against the high wind pressures incident to flying and against small objects in the air. The service requirements of goggles for such users are very severe and very careful designing is essential to meet the requirements satisfactorily. Aside from the requirement of strength in the frame, transparency of the lenses, etc., it is essential that a very soft, carefully fitted cushion be provided between the goggle frame and the wearer's face.

20 An excellent cushion has been developed which consists of a soft ring adapted to be positioned between the goggle frame and the face, which ring may be formed of rubber tube, or preferably of sponge rubber, and which is of different sizes at different portions of its periphery. It is adapted to have the larger portions positioned with respect to the frame in such way that they fit into the hollows in the face alongside the nose, thereby providing a very comfortable cushion which is also durable and which makes a very tight seal between the goggle and the face.

25 Difficulty has however been encountered in attaching the cushion to the frame. It is essential that the cushion be firmly attached so that it will remain in place under the severe conditions of use. It is also desirable that the cushion shall be readily detachable so that it may easily be fitted to the facial contours of the wearer, and readily adjustable from time to time in order that it may be used by different wearers and may be re-fitted to different types of faces. The ready detachability is desirable for the additional reason that it permits the replacement of cushions after a period of wear, if, as may happen under severe service, the rubber loses a portion 30 of its softness and elasticity, or if it is in-

jured by any of the many things which may happen to it.

35 My invention provides a goggle cushion which meets these requirements. I utilize a ring which may be formed of sponge rubber, or of rubber tube of the pneumatic type, having different portions of the periphery of different sizes. I provide an attaching lip, which may desirably be an integral part of the cushion member, and which is preferably 40 formed of rubber of a high degree of elasticity, such as the type of rubber compound commonly used for, and known as "tread stock". Alternatively the elastic portion may be of the same compound as the body of the 45 cushion. The goggle frame is desirably made with an outwardly flaring rim over which the elastic attaching lip is adapted to snap and against the face of which the cushion body 50 is supported.

55 Alternatively the elastic attaching means may be provided in another embodiment by a similar lip, which is desirably stiffened in some convenient way, such as by means of a 55 spring wire or by the incorporation within the attaching lip of a substance which will harden the material of the lip, such as additional sulphur. I then provide a ledge or flange upon the frame of the goggle with which the stiffened lip of the cushion is 60 adapted to cooperate, the stiffened lip being forced past the ledge, into a groove, within which it is held by its own elasticity. The cushion is thus locked to, and firmly attached 65 to the goggle frame. These constructions 65 hold the cushion firmly in place in use, but in either the cushion is readily removed by appropriate pressure upon the cushion, whereafter it may be adjusted in rotative position with respect to the frame, and reattached 70 according to the facial contours of the wearer.

75 By these constructions I am enabled to provide excellent, thick, shaped, cushions in a goggle which are readily adjusted to bring the thicker portions into the hollows of the 80 wearer's face, and when so adjusted are held firmly in place. My cushions are likewise 85 readily adapted to removal from the frame and replacement by other cushions, new or of different character according to the wishes 90 95 100

of the wearer. My constructions are shown in the accompanying drawings from which, and the following description, further details and objects will be apparent:

5 Fig. 1 is a horizontal view, partly in section, of goggles embodying a preferred form of my invention;

10 Fig. 2 is an enlarged sectional view of a portion of the cushion, frame and holding means of my invention;

Fig. 3 is a vertical view of the molded cushion of my invention;

Fig. 4 is a perspective view of the same embodiment;

15 Fig. 5 is a vertical view of an alternative form of the cushions of my invention;

Fig. 6 is a view of a section of an embodiment of the cushion and holding means of my invention;

20 Fig. 7 is a sectional view of an alternative embodiment of the cushion and holding means;

Fig. 8 is a view of an alternative embodiment of a cushion of the "pneumatic" pattern;

25 Fig. 9 is a view in section of the goggle frame and cushion showing the method of attachment of the alternative embodiment, and

Fig. 10 shows an alternative double lip construction.

30 Referring to the figures, I provide goggle frames or eye cups 1 and 2, which are held in proper relationship by a cooperating nose-bridge member 3. Suitable head straps, not shown, are provided, and cushions 4, as indicated. The cushions 4 are desirably made by molding a material such as sponge rubber into a ring of varying cross section as shown in Fig. 3, where the right-hand portion is shown substantially circular in section and the left-hand portion is shown wider in section, being approximately oval. Such a cushion is particularly advantageous, since the larger portion fits more satisfactorily within the hollows of a wearer's face adjacent the nose 35 and the thinner portion fits conveniently against the sides of his face, thereby making a much more satisfactory and much tighter seal against wind and flying objects.

40 Suitable lenses, not shown, are provided at the front of the frames 1 and 2.

The cushions are desirably molded as indicated in Figs. 2 to 6 inclusive, in which 4 represents the cushion body and 5 represents the attaching lip or extension. The cushion body 4 is preferably formed of a sponge rubber compound, such as that produced by the incorporation of ammonium carbonate into the compound. The attaching lip 5 is desirably made an integral part of the cushion 45 and may be formed of the same compound. It is, however, preferably formed of a more elastic and tougher stock, such as is produced by the compound used for "tread stock." Alternatively it is possible to cement the attaching lip to the cushion body by any con-

venient cementing means. The cushion may be molded in any convenient way, and may be in a circular form as indicated in Fig. 5, or may be molded in the oval form having a curved face as indicated in Figs. 3 and 4. It may desirably be formed in a mold of such shape that the center line of the enlarged portion of the body is inclined to the principal plane of the cushion as shown in Fig. 6, with the attaching lip 5 directed inward. When molded in this way, the elastic lip obtains a more substantial hold upon the goggle frame.

70 The goggle frame 1 is desirably equipped with a ledge member or flange 7 as shown in Figs. 1 and 2, over which the attaching lip 5 may be stretched.

75 The elasticity of the cushion and lip then produces a gripping action upon the ledge 7 and the frame 1 which holds the cushion firmly in place. The elasticity of the cushion holds it in place under the flat side of the ledge 7 and thus in proper position for service as a pad between the goggle frame and the wearer's face. When so attached, the cushion is readily removable for replacement by other or new cushions, or for replacement to readjust the larger portions into the hollows of the wearer's face. If desired, the cushion may, after being properly positioned, be cemented in place by the inclusion of a suitable cement between the metal of the frame 1 and the lip 7, and the rubber of the body 4 and the lip 5.

80 This construction utilizes the characteristic elasticity of rubber to obtain a firmer attachment between the cushion and the frame. Other types of elasticity may likewise be utilized for attachment between the goggle frame and the cushion. The elasticity of a stiffened lip may be utilized, by such means as the inclusion of a spring wire within the attaching lip or by stiffening the attaching lip by the inclusion of an excess of sulphur to produce a semihard rubber. An alternative 90

95 embodiment including this type of construction is disclosed in Figs. 7 to 10 inclusive, in which the cushion member 4 has a lip portion 5 molded integral therewith, which is stiffened by a suitable means. This means 100

105 may conveniently be the spring wire member 6 which may conveniently be incorporated within the attaching lip in the operation of molding. Alternatively, the lip member may be made of hardened rubber, such as that containing a suitable proportion of sulphur to produce a compound which will vulcanize to a stiff but not brittle condition.

110 Such a compound is readily made an integral part of the cushion. By this construction a stiffened, elastic, integral spring member is 115 formed as a part of the cushion member. A ledge member 9 is provided as a part of the frame 1, as shown in detail in Figs. 9 and 10. The stiffened lip member of the cushion is 120 adapted to cooperate with the ledge 9 as 125 130 135 140 145 150 155 160 165 170 175 180 185 190 195 200 205 210 215 220 225 230 235 240 245 250 255 260 shown in the figures, by the forcing of the stiffened lip member 5 within it. The spring effect of the stiffened lip then holds it firmly in place adjacent the ledge, and thereby holds the cushion in place.

5 The ledge member 9 is desirably formed by a reverse bending of the material of the frame 1. In the embodiment shown, the metal is desirably bent outward as at 8 and then 10 versely bent inward and upward to form the ledge 9. By this means the bent portion forms a flat member which serves to protect the inner end of the frame 1, and in the event that the cushion is displaced, the flat portion 15 contacts with the wearer's face rather than the sharp edge. By this means the cushion is held firmly in place against the usual forces encountered in service, and provision is made so that in the event of abnormal conditions 20 acting to displace the cushion, no sharp metal edges or corners are exposed which can make injurious contact with the wearer's face.

The cushion member 4 with the lip member 5 and its contained spring 6 may be molded in the proper curved oval form as shown in Figs. 3 and 4. When so molded, it is particularly advantageous since it fits readily within the frame, and may still be adjusted by minor changes in the shape of the spring 25 wire. Alternatively, it may be molded in a substantially circular form as shown in Fig. 5 with the spring wire included in the lip in a substantially circular form. The cushion and wire may then be bent to the proper 30 form by pressure suitably applied. As previously suggested, the lip may alternatively be stiffened by forming it of a rubber compound of a stiffer material than the material of which the cushion body is formed. This 35 may be a rubber compound containing a suitable excess of sulphur to give a semihard compound.

40 For especially severe service, it may be found convenient to provide a double lip construction as shown in Fig. 10, in which the cushion 4 is held in place on the frame 1 by the lip 5 and the incorporated spring wire 6, cooperating with the ledge 9 on the frame 1. An auxiliary surrounding lip 8 45 is provided and fitted over the exterior of the frame 1 to aid in positioning the cushion in place and to prevent contact of the edge of the frame 1 with the wearer's face, in the event that the cushion 4 is rolled sidewise 50 by usual wind forces or other pressures, acting at angle to the normal.

The lip 8 may also be made elastic and caused to interlock with the frame, thus providing a doubly secure attachment of the 55 cushion to the frame, by a clamping effect between the two attaching lips and the frame.

60 By the construction of my invention, the cushion members are conveniently formed by a molding operation, either in sponge rubber, or in the form of rubber tubing to pro-

duce the so-called pneumatic cushion. This 65 operation conveniently produces the cushion, the attaching lip, and the stiffening member as an integral, unitary part. When so formed, the cushions are readily attached to 70 the frames of the goggles, and, in the course of the attachment thereto, are readily adjustable to bring the thicker portions in a proper relationship with the goggle frames, such that they are properly positioned in the 75 hollows of the wearer's face. The cushions are further readily removable for cleaning or other purposes and when so removed are readily readjusted to fit equally well the hollows of another wearer's face, which may be 80 differently positioned from the hollows of the first wearer's face. Likewise the cushions are conveniently removable for replacement at the end of their useful life, or in the event that they are injured by mischance.

85 While I have shown several embodiments 90 of the device of my invention in the accompanying description, it is capable of various other modifications therefrom without departing from the spirit thereof, and it is desired, therefore, that only such limitations shall be imposed thereon as are required by the prior art or indicated by the appended 95 claims.

I claim as my invention:

1. A goggle comprising a tubular eye cup having a flange extending at an angle to the tubular portion and a ring shaped cushion of elastic material, the body of said cushion having a continuous extension of elasticity 100 different from that of the body portion and elastically engaging said flange with the cushion in position with its body portion in rear of said flange.

105 2. A goggle comprising a tubular eye cup having a flange extending at an angle to the tubular portion and a ring shaped cushion, the body of said cushion having a continuous extension and a spring wire embedded within 110 said extension, said extension elastically engaging said flange with the cushion in position with its body portion in rear of said flange.

115 3. A goggle comprising a tubular eye cup having a flange extending at an angle to the tubular portion and a ring shaped cushion of sponge rubber, the body of said cushion having a continuous elastic extension elastically engaging said flange with the cushion in position with its body portion in rear of said flange, said extension being of different elasticity from that of the cushion.

120 4. A goggle comprising a tubular eye cup having at its rear internal and external flanges forming an extended bearing surface 125 and a ring shaped cushion, the body of said cushion having a continuous elastic extension of greater stiffness than the material of the cushion elastically engaging one of said flanges with the cushion in position with 130

its body portion in rear of said bearing surface.

5. A goggle comprising a tubular eye cup having at its rear internal and external flanges forming an extended bearing surface and a ring shaped cushion, the body of said cushion having oppositely disposed continuous elastic extensions elastically engaging said respective flanges and securing the cushion thereto with its body portion in rear of said bearing surface.

6. A goggle comprising a tubular eye cup having a flange extending at an angle to the tubular portion and a ring shaped cushion, the body of said cushion having a continuous elastic extension of greater stiffness than the material of the body portion, said extension elastically engaging said flange and securing the cushion thereto in position with its body portion in rear of said flange.

7. A goggle comprising a tubular eye cup, a flange extending laterally therefrom and formed with a forwardly opening recess, and a ring shaped cushion having a continuous stiffened elastic extension in said recess in engagement with the wall thereof.

8. A goggle comprising a tubular eye cup, a flange extending inwardly therefrom and formed with a forwardly opening recess, and a ring shaped cushion having a continuous stiffened elastic extension in said recess in engagement with the wall thereof.

9. A goggle comprising a tubular eye cup, a flange extending laterally therefrom and formed with a forwardly opening recess, and a ring shaped cushion having a continuous extension, and a spring wire embedded therein, said extension being within said recess and in engagement with the wall thereof.

10. A goggle frame comprising a tubular eye cup the rear portion of which is bent outwardly at an obtuse angle to the eye cup and then inwardly beyond the first bend at an acute angle to the eye cup, to form a wide bearing surface.

11. A goggle comprising a tubular eye cup having an inwardly extending flange and a ring-shaped cushion having a continuous extension containing a spring wire, said extension engaging said flange to secure the cushion thereto in position with its body portion in rear of said flange.

12. A goggle cushion comprising an annular body having an annular extension containing a spring wire.

13. A goggle cushion comprising a flexible annular body having a pair of annular elastic extensions at different distances from its center, the innermost of such extensions being stiffened.

14. A goggle cushion comprising an annular body having a pair of annular elastic extensions at different distances from its cen-

ter and a spring wire embedded in the innermost of such extensions.

15. For a goggle eye cup having a circumferential attaching portion, a cushion comprising an annular elastic body having an axial extension forming an attaching lip, and a circumferential metallic reinforcing member associated with the lip and cooperative with the attaching portion of the eye cup to secure the lip of the cushion thereto.

In witness whereof, I hereunto subscribe my signature.

EMIL B. MEYROWITZ.
